DRAFTING INSTRUMENT

Edward F. Campbell, Jeffersonville, Ind.

Application April 10, 1950, Serial No. 9,083

Term of patent 3½ years

(Cl. D52—1)

To all whom it may concern:

Be it known that I, Edward F. Campbell, a citizen of the United States of America and residing at Jeffersonville, Indiana, have invented a new, original, and ornamental Design for a Drafting Instrument, of which the following is a specification, reference being had to the accompanying drawing, forming a part thereof.

Fig. 1 is a top plan view of the drafting instrument;

Fig. 2 is a bottom plan view of the same;

Fig. 3 is a fragmentary plan view of one of the three removable strips, on an enlarged scale;

Fig. 4 is an edge view of the drafting instrument.

I claim:

The ornamental design for a drafting instrument, as shown.

EDWARD F. CAMPBELL.
